[57] CLAIM

The ornamental design for a double-drawing toy, as shown and described.

DESCRIPTION

FIG. 1 is a top perspective view of a double drawing toy showing my new design;

FIG. 2 is a right side elevational view thereof;

FIG. 3 is a top plan view thereof;

FIG. 4 is a bottom plan view thereof;

FIG. 5 is a left side elevational view thereof;

FIG. 6 is a front elevational view thereof; and

FIG. 7 is a rear elevational view thereof.

The broken line showing of drawing instruments in FIGS. 1, 2, 3, 5, 6, and 7 is for illustrative purposes only and forms no part of the claimed design.

*Fig. 3.**Fig. 4.*FIG. 5.

FIG. 6.

FIG. 7.
